Patented Sept. 18, 1973

228,391

FISHING LURE

John B. Barritt, Jr., 4349 NW. 13th,
Oklahoma City, Okla. 73107

Filed July 12, 1972, Ser. No. 270,979

Term of patent 14 years

Int. Cl. D22—05

U.S. Cl. D22—29

FIG. 1 is a side view of the fishing lure.

FIG. 2 is a view of the lure looking at the right hand side of FIG. 1.

FIG. 3 is a view of the lure looking at the left hand side of FIG. 1.

FIG. 4 is a view of the lure looking at the side opposite the side shown in FIG. 1.

FIG. 5 is a view looking down on the lure as shown in FIG. 1.

FIG. 6 is a view looking up on the lure as shown in FIG. 4.

I claim:

The ornamental design for a fishing lure, substantially as shown.
